FIG.3

FIG.6

Figure 1 is a front perspective view of a portable dishwasher or similar article embodying our new design;

Figure 2 is a top plan view thereof;

Figure 3 is a fragmentary side-elevational view of the top portion of the dishwasher;

Figure 4 is a fragmentary transverse cross-sectional view taken on the line 4-4 of Figure 2;

Figure 5 is a fragmentary cross-sectional view taken on the lines 5-5 of Figure 2;

Figure 6 is a fragmentary cross-sectional view taken on the line 6-6 of Figure 2; and

Figure 7 shows a fragmentary top plan view taken on the line 7-7 of Figure 3.

The side not shown is substantially like the side shown, and the back panel is substantially plain.

We claim:

The ornamental design for a portable dishwasher or similar article, as shown and described.
